WILLIAM M. STEPHENSON, OF DALLAS, TEXAS.

HYDROSTATIC CONTROL FOR PUMPS.

1,290,397.

Specification of Letters Patent.

Patented Jan. 7, 1919.

Application filed October 26, 1917. Serial No. 198,676.

To all whom it may concern:

Be it known that I, WILLIAM M. STEPHENSON, a citizen of the United States of America, residing at Dallas, in the county of Dallas and State of Texas, have invented a certain new and useful Improvement in Hydrostatic Controls for Pumps, of which the following is a specification.

This invention relates to a new and useful improvement in a hydrostatic control for pumps, or automatic pressure governor for use in connection with well pumping systems, and particularly appertains to a form of hydrostatic governor adapted to exercise a controlling relation over the pump with which it is connected.

A purpose of this invention is to provide a compression chamber adapted to be disposed in the well and having connection with an automatically controlled air pressure valve placed in an air pressure line for the purpose of regulating the pressure of the compressed air through said line. The air pressure line herein mentioned is adapted to furnish a continuous pressure, either of gas or air, to a pumping head or engine used for operating the pump of the oil well. The primary purpose of the invention is to therefore provide means for automatically starting and stopping the engine, pumping the oil well at times when the rise of oil in the well will be sufficient to justify the pumping thereof.

With the above and other objects in view the invention has relation to a certain combination and arrangement of parts, an example of which is described in the following specification, pointed out in the appended claims, and illustrated in the accompanying drawings; wherein,

Figure 1 represents a view of the entire system herein described, parts being shown in section and parts being shown in elevation.

Fig. 2 illustrates a form of pressure regulating valve and correlated parts.

Fig. 3 illustrates a front sectional view of the device shown in Fig. 2.

Referring now more in particular to the drawings, wherein the same parts throughout are designated by the same reference characters, the numeral 1 indicates a form of tubular well casing, well known to those conversant in the art. This casing has its head at the ground surface and extends to the oil bearing strata below where it ter-

minates in an open end adapted to receive the oil thereinto. A usual form of discharge pipe 2 is provided to discharge the oil from the depths of the well. A strainer tube 3 is usually provided on the lower extremity of the discharge pipe. A valve 4 is disposed in the lower extremity of the discharge pipe. The usual form of piston 5 and connecting rod 6 is arranged in the working barrel of the cylinder 7 which has connection with the discharge pipe and may be considered a continuation of said pipe 2. This connecting or sucker rod, as it is known to those conversant in the art, extends throughout the length of the discharge pipe and has connection with a piston rod 8 of a steam or air head 9 of any appropriate design and power. Any form of motive power or engine 9 may be used, and it may receive its power from steam, compressed air or gas. It very often occurs that high pressure gas is available from gas wells in and about the vicinity of oil fields and, in such cases, motive power may be applied to the motor from such source. This provides a most economical source of power and where the power from the pressure of a gas well is connected up with this system of automatic pump control it is possible to pump individual oil wells on a very economical basis.

An open receptacle or oil receiving chamber 10 is secured upon a cover plate 11 which receives and supports the discharge pipe 2. This chamber is provided with a cover plate 12 giving access to the interior thereof where the stuffing box or other parts correlated with the piston rod may be adjusted. This oil receiving chamber also acts as a supporting base for the pumping engine. An oil discharging pipe 13 has connection with the oil receiving chamber 10 and discharges oil to any point of storage or receiving reservoir. A check valve 14 should be included in the pipe line 13 for preventing the oil from running back into the chamber 10.

A substantially long tubular compressing chamber 15 is disposed in the well and supported by the discharge pipe 2. The upper extremity of the compression tube is formed air tight through a coupling member 16 screw-threaded upon the discharge pipe and in like manner receiving the tube 15. The lower extremity of the compression tube 15 is left open for the purpose of admitting the rising oil.

A pressure regulating device is disposed upon the engine for the purpose of controlling the steam, air or gas to the motor for operating same. This device comprises a diaphragm chamber composed of two shell like halves 10 secured to flanges integrally formed with the cylinder of the engine. A flexible rubber diaphragm 11 is interposed between the two halves and adapted to remain in normal position as illustrated in Fig. 2. A metal disk 12 is adapted to lie in contact with the flexible diaphragm. This metal disk is integrally attached to one extremity of a gear rack 13. The gear rack 13 projects through an opening in the shell or diaphragm casing and has its outer end slidably confined in a guide 20 for the purpose of confining it to a straight line movement when undergoing displacement. A pinion 21 is fixed upon a shaft 22 and engages the gear rack. The shaft 22 is journaled in an air box 16 fixed upon the diaphragm casing 10. The inner extremity is provided with a lifting cam 23. This cam is confined between a pair of disks 24 fixed upon a lift valve which comprises a stem 25 vertically disposed in the air box and having attached to the lower extremity thereof a valve head 26 adapted to normally rest in a closed position with the open end of pipe line 27. This pipe 27 connects with the air box and with the pressure chest 9 of the motor. A pipe line 28 connects with the air box adapted to furnish same with an inexhaustible pressure supply of air, gas or steam, which ever is to be used in the operation of this system. A substantially small pipe line or tube 29 connects with the base of compression chamber 15 and extends to the diaphragm chamber where it has open communication therewith. This places in direct connection the one side of the diaphragm chamber with the compression tube at the bottom of the well.

In comprehending the operation of this automatic pumping system it will be understood that the oil gradually rises in the well casing until it has attained a considerable depth therein. This will cause the oil to rise inside of the compression tube trapping the air in the upper portion thereof as it enters said tube. As the oil continues to rise in the well casing it may go considerably above the compression chamber, finally submerging it. This will create a considerable pressure on the air trap within the tube, which air will exert its pressure throughout the length of the tube 29 into and against the diaphragm 11 contained in the diaphragm chamber. When the pressure becomes sufficiently great the diaphragm will undergo an expansive displacement causing the gear rack to move outwardly thereby revolving the pinion and lifting the valve 26 from its seat. This uncovers the port of the pipe 27

and permits the flow of the pressure from the pipe line 28 to the engine thereby setting it in operation. The pumping operation will continue until the accumulated oil in the well casing has been discharged upwardly to through the discharge pipe 9 in the chamber 10 and outwardly through the emptying pipe 28 after which the oil will finally drop below the level of the compression chamber which releases the air therefrom. This permits the pressure behind the diaphragm to pass from the diaphragm chamber, which permits the return to normal position of all parts, thereby stopping the flow of the pressure from the pipe 28 into the engine. The pumping machine will remain idle until the oil has again risen to a sufficient height therein to set the engine to run, as above described.

The invention is intended to include all such changes in design and form as may be considered to come within the meaning of the following claims.

Claims:

1. In a pumping system of the character described, the combination with any form of motive power such as an engine for operating a pump, a pipe line including a control valve to supply the engine a driving agent such as steam or other pressure, a pump and discharge pipe disposed in the well and in operative connection with the motive power, of a tubular compression chamber disposed in the well and supported therein by the discharge tube, a pipe line connecting with the compression chamber and extending to the ground surface, and means connected with the pipe line for operating the valve to control the action of the engine.

2. In a hydrostatic control system for pumps, the combination with a well casing, of a compression chamber comprising a tube with one end sealed and the other end formed open disposed in the well casing with the open end downwardly directed, a discharge pipe extending through the well and supporting the compression chamber by being screw-threaded into the well and into said compression chamber, a pump mechanism confined in the compression chamber and extending through said tube and compression chamber, the discharge pipe thus leaving an annular air space within the compression chamber which will become an air trap when filled with oil rising into said compression chamber, the said pump cylinder a piston, the connection of the pump oil discharge pipe to the oil upwardly through the discharge tube, a valve box for starting and stopping the engine, and a pipe line connecting the valve box with the compression chamber for the purpose of registering the hydrostatic pressure of the air lock within the compression chamber into and against the mechanism of the valve box when liquid to be pumped rises into the well casing and into the com-

pression chamber thus enabling the engine to be automatically started and stopped by the rise of said liquid into the aforesaid well parts.

5 3. In a well pumping apparatus, a pipe line through which liquid may be discharged from a well, a pumping means employed to carry out the aforesaid purpose, a compression chamber attached to the discharge pipe

and having one end thereof sealed and the other end formed open, a pipe line connected with the compression chamber and connecting with the pumping means for establishing a control over said pumping means.

In testimony whereof I hereunto affix my 15
signature.

WILLIAM M. STEPHENSON.
